BATH FIXTURE

Charles F. Riddell, New York, N. Y.

Application November 29, 1935, Serial No. 52,261
Renewed January 19, 1937

13 Claims. (Cl. 4—149)

My invention relates to bathtub fixtures, and more particularly to bathtub fixtures adapted to be used with shower curtains, where the tub is arranged to have a shower. Accidents often happen in bathtubs because of the smooth, slippery surface of the tub. Getting into and out of tubs is dangerous, and has often resulted in injury.

Moreover, the curtain of a tub is often insecurely held in position at its edge, which occupies a median position in the tub, and water will often run off the curtain onto the floor.

It is an object of my invention to provide a fixture which will minimize the danger incident to getting into and out of bathtubs which are equipped with showers.

A further object of my invention is to provide a device for holding the shower curtain so as to minimize the danger of water being spilled on the floor of a bathroom.

Yet another object of my invention is to provide a device which is simple to construct, easy to repair and replace, and which can be manufactured at small cost.

With these and other objects in view, which may be incident to my improvements, the invention consists in the parts and combinations to be hereinafter set forth and claimed, with the understanding that the several necessary elements comprising my invention may be varied in construction, proportions and arrangement, without departing from the spirit and scope of the appended claims.

In order to make my invention more clearly understood, I have shown in the accompanying drawings means for carrying the same into practical effect without limiting the improvements in their useful applications to the particular constructions, which, for the purpose of explanation, have been made the subject of illustration.

In the drawings,

Fig. 1 is a perspective view showing my device in position on a bathtub equipped with a shower curtain;

Fig. 2 is a view taken along the line 2—2 of Figure 1, looking in the direction of the arrows;

Fig. 3 is a view taken along the line 3—3 of Figure 2, looking in the direction of the arrows;

Fig. 4 is a view taken along the line 4—4 of Figure 1, looking in the direction of the arrows;

Fig. 5 is a view taken along the line 5—5 of Figure 4, looking in the direction of the arrows;

Fig. 6 is a perspective view of a modified form of my invention;

Fig. 7 is a view taken along the line 7—7 of Fig. 6, looking in the direction of the arrows;

Fig. 8 is a view taken along the line 8—8 of Fig. 7, looking in the direction of the arrows.

Referring to the drawings, I have shown an upright 1 provided with a stirrup member 2 which fits over an edge 3 of a bathtub 4. At its upper end the upright 1 is provided with a slideable member 5 which is adapted to slide over a curtain rod 6. On the curtain rod 6 is a shower curtain 7 which is attached to the curtain rod 6 by means of sliding metal loops 8 of the usual construction. The end of the curtain is provided with an eye 9 and an eye 10 at its bottom. A link 11 is attached through eye 9 and fits over the upper part of the upright 1. Likewise, a link 12 passes through the eye 10 and fits over the lower part of the upright 1.

The upright 1 is so constructed as to permit adjustment of its length to accommodate the varying distances between curtain rods and tub edges of different types of installations. The upright 1 is adapted to fit within an annular extension 13 on the stirrup member 2. At the top of the annular extension 13 is a split section 14 provided with splits 15 and a frusto conical end 16. The split section 16 is provided with screw threads, indicated at 17, which are adapted to engage screw threads 18 formed on a knurled annular tightening element 19 which has a frusto conical interior surface 20 that is adapted to fit over the frusto conical surface 16 of the element 14.

By tightening up the knurled annular tightening member 19 by screwing it on the extension 14, the split portion of the element 14 is clamped firmly against the upright 1 and prevents movement of the rod within the extension 13 of the stirrup 2. This arrangement permits the upright 1 to be adjusted to varying distances between curtain rod 6 and tub edge 3.

The stirrup 2 is provided on its upper interior with rubber nipples 21 which permit the stirrup 2 to slide over the edge of the tub without danger of marring the edge. On one side of the stirrup 1 I have provided friction pads 22 which may be of rubber or leather, or some other suitable material. On the other side of the stirrup 1 I have provided a thickened portion 23 through which is threaded at 24 a screw threaded clamp 25 which is provided with an operating handle 26. The stirrup 2 is adapted to be held in place by moving the operating handle 26 to screw the screw clamp 24 firmly against the edge of the

tub 3, whereby the device is readily and firmly held in place.

In order to facilitate the movement of the 5 slidable element 5 on the curtain rod 6, I have constructed the element 5 in the form of a stirrup provided with four bolts 26 which pass above and below the curtain rod. Mounted on each bolt within the stirrup 5 is a roller 27. The curtain rod 6 rides on the rollers 27 and this construction 10 forms an anti-friction engagement with the curtain rod 6. The stirrup 5 is screw threaded, as indicated at 28, to the upright 1.

It is to be noted that the construction of the 15 stirrup 5 is such as to cause the rollers 27 to bear on the curtain rod 6 at points somewhat remote from each other, which tends to prevent binding of the device when it is pulled by means of the upright 1 from one position to another by the hand of the user. If the rollers 27 are 20 mounted too close together, there will be a tendency for binding to occur.

In use the upright 1 is moved to the desired 25 position by the hand of the user who grasps the upright 1 and loosens the screw clamp by turning the handle 25. When the curtain is pulled to the desired position, the handle 25 is moved to tighten the screw clamp and the user can use the shower with confidence that water will not spill from the curtain onto the floor.

30 Further, and quite important, is the use of the upright 1 in getting into and out of the slippery bathtub. The upright 1 can be grasped by the hand of the user to steady himself in getting into and out of the tub, and even while taking 35 a shower.

In Figures 6, 7 and 8 I have shown another 40 form of my device in which the upright 1 is attached to a T-fitting 100 which is adapted to slide over the curtain rod 6. The T-fitting 100 is not provided with anti-friction members, but with reasonable care, binding between the T-fitting 100 and the rod 6 will not be excessive. The end of the upright 1 is provided with a stirrup 101 which is lined with an anti-friction material 102 such as rubber or leather. The stirrup 101 is so made as to have a spring pressure 45 against the edge 3 of the tub 4. This spring pressure tends to hold the upright 1 in any desired adjusted position. However, because the 50 spring pressure is not excessive, the operator can move the upright to any desired position.

While I have shown and described the preferred embodiment of my invention, I wish it to be understood that I do not confine myself to 55 the precise details of construction herein set forth, by way of illustration, as it is apparent that many changes and variations may be made therein, by those skilled in the art, without departing from the spirit of the invention, or exceeding the scope of the appended claims.

I claim:

1. A bath fixture comprising a tub having an edge, a shower bath curtain rod, a curtain slidably mounted on the rod, and a movable upright 65 attached to the curtain and slidably on the tub edge and the curtain rod.

2. A bath fixture comprising a tub having an edge, a shower bath curtain rod, a curtain slidably mounted on the rod, a movable upright 70 attached to the curtain and slidably on the tub edge and the curtain rod, and means to attach the lower end of the upright to the tub edge.

3. A bath fixture comprising a tub having an edge, a shower bath curtain rod, a curtain slidably mounted on the rod, a movable upright at-

tached to the curtain and slidably on the tub edge and the curtain rod, and means to regulate the length of the upright.

4. A bath fixture comprising a tub having an edge, a shower bath curtain rod, a curtain slidably mounted on the rod, a movable upright attached to the curtain and slidably on the tub edge and the curtain rod, means to attach the lower edge of the upright to the tub edge, and means to regulate the length of the upright. 10

5. A bath fixture comprising a tub having an edge, a shower bath curtain rod, a curtain slidably mounted on the rod, a movable upright attached to the curtain and slidably mounted on the curtain rod, a stirrup adapted to fit over the 15 tub edge attached to the upright, and means on the stirrup to hold it from slipping on the tub edge.

6. A bath fixture comprising a tub having an edge, a shower bath curtain rod, a curtain slidably mounted on the rod, a movable upright attached to the curtain and slidably mounted on the curtain rod, a stirrup adapted to fit over the tub edge attached to the upright, and a screw clamp fitting through one side of the stirrup to 20 hold it in place on the edge of the tub.

7. A bath fixture comprising a tub having an edge, a shower bath curtain rod, a curtain slidably mounted on the rod, a movable upright attached to the curtain and slidably mounted on the curtain rod, a stirrup adapted to fit over the tub edge attached to the upright, and anti-friction means in contact with the curtain rod and carried by the upright to facilitate the movement 30 of the upright on the rod. 35

8. A bath fixture comprising a tub having an edge, a shower bath curtain rod, a curtain slidably mounted on the rod, a movable upright attached to the curtain and slidably mounted on the curtain rod, a stirrup adapted to fit over the tub edge attached to the upright, anti-friction means in contact with the curtain rod and carried by the upright to facilitate the movement 40 of the upright on the rod, and means to regulate the length of the upright. 45

9. A bath fixture comprising a tub having an edge, a shower bath curtain rod, a curtain slidably mounted on the rod, a movable upright attached to the curtain and slidably on the curtain rod, means to regulate the length of the upright, 50 a stirrup adapted to fit over the tub edge attached to the upright, and means on the stirrup to hold it from slipping on the tub edge.

10. A bath fixture comprising a tub having an edge, a shower bath curtain rod, a curtain slidably mounted on the rod, a movable upright attached to the curtain and slidably on the curtain rod, means to regulate the length of the upright, a stirrup adapted to fit over the tub edge attached 60 to the upright, means on the stirrup to hold it from slipping on the tub edge, and a screw clamp fitting through one side of the stirrup to hold it in place on the edge of the tub.

11. A bath fixture comprising a tub having an edge, a shower bath curtain rod, a curtain slidably mounted on the rod, a movable upright attached to the curtain and slidably on the curtain rod, means to regulate the length of the upright, a stirrup adapted to fit over the tub edge attached 70 to the upright, means on the stirrup to hold it from slipping on the tub edge, a screw clamp fitting through one side of the stirrup to hold it in place on the edge of the tub, and an anti-friction means in contact with the curtain rod and car- 75

ried by the upright to facilitate the movement of the upright on the rod.

12. A bath fixture comprising a tub having an edge, a shower bath curtain rod, a curtain slidably mounted on the rod, a movable upright attached to the curtain and slidable on the curtain rod, a spring stirrup adapted to fit over the tub edge attached to the upright whereby the spring of the stirrup tends to prevent sliding of the stirrup on the tub edge.

13. A bath fixture comprising a tub having an

edge, a shower bath curtain rod, a curtain slidably mounted on the rod, a movable upright attached to the curtain and slidable on the curtain rod, a spring stirrup adapted to fit over the tub edge attached to the upright whereby the spring of the stirrup tends to prevent sliding of the stirrup on the tub edge, and friction padding on the inside of the stirrup to prevent marring of the tub edge and to furnish an anti-slip grip.

10
